EX

OR D. 12,178

DESIGN FOR COOKING-STOVE.

Design No. 12,178, dated February 22, 1881.

UNITED STATES PATENT OFFICE.

GARRETTSON SMITH, OF PHILADELPHIA, ASSIGNOR TO OLIVER B. KEELEY,
OF SPRING CITY, PENNSYLVANIA.

DESIGN FOR COOKING-STOVE.

SPECIFICATION forming part of Design No. 12,178, dated February 22, 1881.

Application filed January 18, 1881. Term of patent 7 years.

To all whom it may concern:

Be it known that I, GARRETTSON SMITH, a citizen of the United States, residing in Philadelphia, Pennsylvania, have invented or produced a new and original Design for a Cooking-Stove, of which the following is a specification.

My design is fully shown in the accompanying drawing, which represents a perspective view of the stove.

The main oven-door has a beveled edge, *a*, an ornamental border, *b*, a central panel, *d*, and foliated ornaments *e*. The central panel, *d*, is of oval form with beveled edges and a flat face with the initial of the name of the stove.

The end door of the fire-place has a beveled edge, *f*, and a central ornament, *g*, inclosed in a border, *h*.

Each of the front fire-place doors has two

mica panels, *i*, and on each side of the fire-place is an ornamental panel, *m*.

The prominent ornament of each foot *n* is a Maltese cross in an oval medallion.

I claim—

1. The design for the oven-door, said design comprising, essentially, the border *b*, central panel, *d*, and ornamentation *e*, as shown and described.

2. The design for the entire stove, said design comprising the oven-door, end fire-place door, front fire-place doors, panels *m*, and feet *n*, all ornamented as shown and described.

In testimony whereof I have signed my name to this specification in the presence of two subscribing witnesses.

GARRETTSON SMITH.

Witnesses:

EMELINE JONES,
HARRY SMITH.
